US0D1071668S

(12) **United States Design Patent** (10) **Patent No.:** **US D1,071,668 S**
(45) **Date of Patent:** **** Apr. 22, 2025**

(54) **CUP HOLDER**

(71) Applicant: **Yiwu Chengshen Technology Co., Ltd,**
Zhejiang (CN)

(72) Inventor: **Zuxing Chen**, Zhejiang (CN)

(**) Term: **15 Years**

(21) Appl. No.: **29/960,498**

(22) Filed: **Aug. 30, 2024**

(30) **Foreign Application Priority Data**

Jul. 26, 2024 (CN) 202430472605.5

(51) **LOC (15) Cl.** **07-09**

(52) **U.S. Cl.**
USPC **D7/600.4**

(58) **Field of Classification Search**

(57) **CLAIM**

The ornamental design for a cup holder, as shown and described.

DESCRIPTION

FIG. 1 is a top perspective view of a cup holder, showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is a perspective view showing the exploded state of the cup holder when disassembled into single and double layers.

1 Claim, 8 Drawing Sheets
